DISPENSING APPARATUS FOR TABLETS AND THE LIKE

John Turgill, London, and Samuel James Everett, Thornton Heath, England, assignors of one-third to Jack Seward Cottrell, London, England

Application September 29, 1931, Serial No. 565,812
In Great Britain October 2, 1930

3 Claims. (Cl. 312—48)

This invention relates to improvements in dispensing apparatus for tablets and the like and is more particularly concerned with apparatus used by dentists for delivering tablets one or more at 5 a time without the tablets being touched by hand.

The principal object of the present invention is to provide a simple construction of apparatus consisting of few parts and adapted for ensuring the ready delivery of the tablets without the risk 10 of the tablets jamming in the apparatus. A further object is to enable the apparatus to be quickly refilled with tablets without any particular care being exercised and to avoid handling of the tablets during the operation. Still further objects 15 are to provide a compact construction for receiving a large number of tablets and to provide an improved delivery mechanism for avoiding crushing of the tablets.

According to the invention the apparatus comprises an upright magazine adapted for receiving 20 a pile or piles of tablets superposed edgewise, in combination with means for delivering the tablets one at a time from the apparatus. The magazine may be adapted for containing a number of piles 25 by being formed or provided with a number of vertical passages and further adapted for being adjusted for bringing any one of the passages into communication with the delivery chamber or outlet of the apparatus. Thus as the pile in any one 30 passage is exhausted, the magazine may be rotated to bring the pile of another passage above the delivery chamber or outlet. Owing to the provision of a plurality of passages it will be seen 35 that a large number of tablets can be received in a magazine of compact size and not of undue height. This magazine may comprise a cylindrical core member formed with a number of vertical grooved passages around its circumference and closely enclosed by an outer sheath member the 40 grooved passages being shaped for receiving the tablets superposed edgewise. The sheath member which may be transparent, or formed with windows or sight openings for observing the condition of the piles in the passages, extends above the top of the core member. The latter may be 45 formed with a domed top or may be otherwise shaped so as to have a distributive effect. Thus as the tablets are emptied into the top of the magazine they are guided by the top of the cylindrical core member and are constrained to fall into respective grooved passages and assume the desired edgewise position. Therefore there is no 50 necessity for any particular care to be exercised in filling the magazine and this operation does not necessitate any handling of the tablets. Suitable means such as a spring-pressed ball or plunger 55 may be provided for holding the rotatable magazine in any selected position of adjustment.

The delivery control means for the tablets may be in the form of a rotary valve device chambered 60 to receive the lowermost tablet of a pile and adapted for permitting discharge of the tablets one at a time from the delivery chamber. According to a modification a slidable control means, 65 may comprise a shutter having two prong members which are adapted for engaging in the spaces between superposed tablets arranged edgewise and thereby shutting off communication between the pile and the delivery chamber when the shutter is operated for delivery of a tablet. This 70 delivery device may be adapted for operation by the pressure of a tumbler or drinking vessel.

In order to enable the invention to be readily understood reference will be made to the accompanying drawings illustrating by way of example 75 practical constructions for carrying the invention into effect, in which drawings:—

Figure 1 is a sectional elevation of a magazine containing a number of piles of tablets and fitted 80 with a rotary delivery valve.

Figure 2 is partly an elevation and partly a vertical section on the line 2—2 of Figure 1.

Figure 3 is a plan of Figure 1, with the closure cap removed.

Figure 4 is a perspective view of the rotary 85 valve device shown in Figure 1.

Figure 5 is a side elevation of a dispensing device similar to that shown in Figure 1 but fitted 90 with a slidable delivery device.

Figure 6 is partly an elevation and partly a 95 section on the line 6—6 of Figure 5 and

Figure 7 is a plan view of the slidable delivery device seen in Figures 5 and 6.

According to Figures 1 to 4 a magazine *n* is adapted for receiving a number of piles of tablets 95 arranged edgewise. The magazine extends upwardly from the horizontal member *o* of an angle bracket, the depending vertical member *p* of which is provided with clamps *q* for securing the device to a suitable support. The magazine comprises an upstanding core member *r* formed around its circumference with a series of longitudinal grooved passages *s*. The lower end of the core is fixedly mounted in a disc *t* which is revolvably supported on the bracket member *o* and secured by a bolt *u*. The disc *t* is formed with a circumferential bead *v* forming a socket for receiving the lower end of a transparent cylinder or sheath *w*, made of glass or mica for example, and adapted for fitting closely around the core 110 member *r*. The cylinder *w* closes the open sides of the grooved passages *s* and is taller than the core. The top of the core member *r* is domed at *x* or is of other suitable shape, so that when tablets are emptied into the space above the top 115 of the core they are distributed towards the en-

closing cylinder *w* and are thus directed into the grooved passages *s*. The disc *t* is formed with a number of apertures *y* coinciding with the lower ends of the grooved passages *s* and is rotatable to bring any one of such apertures into communication with a delivery outlet *z*. The latter extends through the horizontal bracket member *o* and is controlled by a rotary valve device 1. This device comprises a plug 2 revolvably fitted in the end of the horizontal bracket member *o*, a grub screw 3 engaging a groove 4 for preventing withdrawal. A crescent member 5 formed on the plug extends into the delivery opening *z*. The rotary device is operated by a crank handle 6 the weight of which normally causes the crescent to be turned for closing the delivery outlet as seen in Figure 1. In this position the lowermost tablet of the particular pile in position above the outlet is held in the delivery outlet by the crescent. When the valve is turned by the handle 6 this tablet is delivered into a tumbler or the like held beneath the apparatus. At the same time the crescent 5 shuts off the remainder of the pile so that only the one tablet is delivered at a time. As soon as the supply of tablets in one pile of the magazine is exhausted, the magazine is rotated by turning the disc *t* to bring the next pile into position above the delivery opening. The correct position with the appropriate passage *s* and aperture *y* coinciding with the delivery opening *z* is determined by a spring-pressed ball or plunger 7, mounted in the bracket member *o*, clicking into one of a series of recesses or depressions 8 formed on the undersurface of the disc *t*. When the tablets in all the piles have been delivered, a removable closure 9 on the cylinder *w* is removed and the magazine is quickly charged by simply emptying tablets into the top of the magazine whence they quickly assume an edgewise position superposed in piles as previously described.

Referring to Figures 5 to 8, the magazine *n* is of similar construction to that just described and is rotatably mounted in any suitable manner. The delivery of the tablets is controlled by a slidable shutter 10. The latter comprises a shutter plate 11 slidable on the undersurface of the horizontal bracket member 12 and formed with a slot 13 for permitting delivery of a tablet from the delivery chamber 14. The plate 11 is formed with a right angled bend 15 extending over the free end of the bracket member 12. This bend is narrower than the shutter plate 11 and its end is formed with two prongs or extensions 16 which are adapted to shut off communication between the magazine and the delivery chamber 14. A presser plate 17 depends vertically from the free end of the shutter plate 11 and a compression spring 18 acts between the presser plate 17 and the vertical bracket member 19 for forcing the slidable shutter outwardly. In this position the prongs 16 permit a tablet to fall from the magazine into the delivery chamber 14 but delivery from the latter is prevented by the shutter plate 11. The presser plate 17 may be pushed back by a tumbler pressed against it and may be appropriately bent for the purpose. When the shutter is pushed back the slot 13 comes beneath the delivery chamber 14 so that the tablet therein falls into the tumbler. At the same time the two prongs 16 pass underneath the passage *s* of the magazine and hold the next tablet of the pile. These prongs are spaced apart and are shaped for engaging spaced points around the circumference of the tablet so that the liability of crushing the latter is eliminated. A stud 20

depending from the bracket member 12 may engage in a slot 21 formed in the shutter plate 11 for guiding it and limiting its sliding movement.

We claim:

1. A dispensing device for disc like tablets comprising a support formed with a delivery chamber, an upright magazine extending upwardly from said support and comprising a cylindrical core member having a domed shaped top and formed with a plurality of vertical passages around its circumference each adapted for reception and guidance of a pile of tablets superposed edgewise, a sheath member enclosing said core, a rotatable mounting for said magazine permitting it to be adjusted to bring any one of said passages into communication with said chamber, and delivery means controlling the admission and delivery of tablets on edge to and from said chamber comprising a slidable shutter controlling the outlet from said chamber and normally supporting the lowermost tablet of a pile and prongs on said shutter plate adapted to engage points on the periphery of the tablet next above and so shut off and temporarily support the pile when the delivery means is actuated for delivery of a tablet, and a spring normally urging the slidable plate to the shut-off position.

2. A dispensing device for disc like tablets comprising a support formed with a delivery chamber, a magazine upstanding from said support and comprising a cylindrical core member having a domed shaped top non-revoluble on said core and formed around its circumference with a number of vertical laterally open passages separated by narrow ribs and shaped to receive the tablets superposed edgewise, a rotatable mounting for said magazine permitting it to be adjusted to bring any one of said passages into communication with said chamber, an outer transparent sheath closing said open passages and extending above the domed top of the core and co-operative with said core to constrain the tablets to assume an edgewise disposition in said passages, and control means normally supporting the lowermost tablet of the pile and operative independently of the rotatable mounting for releasing said tablet and shutting off the remainder of the pile.

3. A dispensing device for disc-like tablets comprising in combination a support formed with a delivery chamber, valve-like means in said chamber and operative for releasing the lowermost tablet of a pile and shutting off the remainder of such pile, a rotatably adjustable mounting on said support, and a magazine erected on said mounting, said magazine comprising a core and a transparent sheath of greater height than said core, the latter being formed with a number of longitudinal peripheral grooves separated by narrow ribs and having a domed top non-revoluble on the core, and the sheath closely surrounding the core so as to enclose the open sides of the grooves and maintain tablets in edgewise position in the piles therein, and co-operating with the domed top to provide a converging throat in which the tablets tilted by the domed top are constrained to assume an edgewise position for admission into said grooves the extension of the sheath above the core forming a charge hopper into which tablets may be poured whereupon they are automatically distributed by the dome to the several piles in edgewise condition.

JOHN TURGILL.
